(57) **CLAIM**

The ornamental design for an expeller, as shown and described.

DESCRIPTION

FIG. 1 is a perspective view of the expeller showing our new design;

FIG. 2 is a top view thereof;

FIG. 3 is a bottom view thereof;

FIG. 4 is side view thereof;

FIG. 5 is an opposing side view thereof;

FIG. 6 is an end thereof; and,

FIG. 7 is an opposing end view thereof.

The broken lines in the drawings illustrate the portions of the expeller that form no part of the claim.
